METHOD AND APPARATUS FOR REMOVING SAMPLE OR TEST PIECES FROM TRAVELLING SHEET MATERIAL

Noel Edward Norman, Ivanhoe, Victoria, and Richard Wilson Maddern, Belmont, Geelong, Victoria, Australia, assignors to Australian Paper Manufacturers Limited, South Melbourne, Victoria, Australia, a company of New South Wales

Application May 24, 1954, Serial No. 431,918

Claims priority, application Australia June 23, 1953

11 Claims. (Cl. 164—17)

This invention relates to a method of and apparatus for removing sample or test pieces from moving sheet material for the purpose of enabling various properties of the material to be ascertained or determined while the sheet is in motion during the course of manufacture or while it is undergoing some industrial treatment or processing.

In the paper making art it is often desired to take samples from a travelling web of paper or board in order to ascertain the moisture content of the travelling web. In cases where the web is travelling at medium or high speed, frequent and accurate determination of moisture content of the web at various laterally spaced positions although highly desirable has been impracticable. Thus, it is very difficult or impossible to remove sample pieces from a travelling sheet in the wet condition without causing complete lateral rupture of the sheet whereupon a great deal of time and labour is required to re-thread the broken sheet through the machine. Sample pieces can be cut from the marginal edges of a travelling web by an experienced and skilful operator without causing breaks, but it is not possible to obtain sample pieces from various positions across the width of the sheet.

Furthermore, with conventional sampling methods it is not possible to avoid loss of moisture from the sample pieces due to (a) handling of the sample piece prior to examination or the sealing thereof and/or (b) the interval that elapses between the time of actually removing the sample piece from the travelling sheet and the time of sealing the sample piece prior to the examination or test for moisture content. In this connection it will be appreciated that loss of moisture occurring between removal of the sample piece and the sealing or examination thereof prevents accurate determination. The loss of moisture is comparatively rapid especially in the case of hot sample pieces taken from the web as it approaches the dry end of a paper making machine.

The present invention contemplates a method and also an apparatus or devices whereby the removal of sample pieces from any appropriate portion of a travelling web of sheet material or the like may be readily and conveniently effected without especial skill or experience on the part of the operator and without likelihood of the web being broken or torn.

The method involves causing a missile having an endless cutting edge to be projected through the travelling web at such speed that a sample piece of predetermined size and shape can be removed from any desired part of the web without liability of the web being ruptured or torn. The method also proposes automatic capture of each sample or test piece and the sealing of it in such manner as to prevent any significant change in its condition pending examination.

While the invention has been devised more especially

2

for use in connection with testing the moisture content of paper or board while travelling in web form through the machine, and will be so described hereinafter, it is believed to be equally applicable in the manufacture or processing of plastics, textiles, metal foil and other sheet material where it is desired from time to time to ascertain certain conditions or properties of the material while it is in motion at more or less high speed. For example, in the case of plastic sheet it may be necessary or advisable for the operator to be able to ascertain periodically such things as the vapour permeability, or the caliper (uniformity of thickness) of the material without stopping or decreasing the speed of travel of the sheet.

The method of the invention and the advantages thereof will be more readily appreciated from the following description and accompanying drawings relating to various alternative devices by which the method may be carried into effect. In the drawings:

Fig. 1 is a sectional view of a device according to one embodiment of the invention.

Fig. 2 is a part sectional view of another form of device.

Fig. 3 is a part sectional view of another form of device.

Fig. 4 is an end view of Fig. 3.

Fig. 5 is a sectional view of an adaptor which may be used for applying the missile in a pistol-like projector.

Thus, according to the embodiment of Fig. 1, the device includes a tubular member 2 connected by a pipe 3, with a source of compressed air or gas which may be admitted, under control of valve 4, into the chamber 6 of the tubular member 2. The latter may be interconnected by a quick releasable coupling 7 with another tubular member 8 within which the missile 9 is normally housed and within which the missile has a sliding fit. Gaskets 11 may be interposed between the adjacent ends 35 of the tubes 2 and 8 and a rupture disc 12 may be inserted between the two gaskets. Disc 12 may be composed of any suitable material such as paper, plastic film, metal foil, which will rupture at the required pressure which may, for example, range from say 30 to 60 lbs. per square inch.

40 The missile 9 may take various forms but will usually be of hollow cylindrical shape having a closing wall 13 towards its rear and having its forward end provided with two or more V-shaped recesses. The endless cutting edge 16 is appropriately sharpened.

In operation, when a predetermined pressure is reached in chamber 6, the disc 12 is ruptured and the missile 9 is projected at high speed from the housing 8 so as to travel through the travelling web 17 at any position of 50 its width selected by the operator. The missile with the removed sample or test piece, which will in all probability come to rest against or near the closing wall 13, may be brought to rest in a box or like receptacle 18 disposed behind the travelling web. This receptacle may be charged with straw or other suitable material 19 which will cushion the impact of the missile.

55 By imparting sufficiently high velocity to the missile, it becomes unnecessary for the travelling web to be in contact with a backing member or support. The inertia of even this paper has been found sufficient to result in a clean-cut sample piece being removed from the travelling web by the missile.

If the sample pieces are required for moisture determination or in cases where the sample might be detrimentally affected by exposure or by the cushioning material, a protective foil or film 21 may be placed over or in front of the cushioning material so that after passing through the travelling web the missile then passes through the film or foil 21 so that a portion is cut therefrom and, in effect, seals the sample piece within the missile.

If the propellant consists of an explosive charge then the device may resemble a pistol adapted to operate with an explosive charge in the form of a blank cartridge of say 0.22" calibre, the pistol being provided with breech and trigger mechanism of any appropriate form. Thus referring to Fig. 2 a barrel member 22 for housing the missile, may have an externally screw threaded neck 23 at its rear end for screwing into an internal thread formed in the front end of the pistol barrel 24. Normally, the missile would be disposed within the barrel 22 as seen in Fig. 2 from which it is projected at high velocity upon "firing" of the pistol. The forward end portion of the barrel 22 may have a series of vent holes 22a for the escape of the explosive gases.

It will be appreciated that the action of the missile when projected by the pistol of Fig. 2 is the same as when propelled by the device of Fig. 1.

According to another embodiment, the device is in the nature of a captive missile pistol. In such a case, the pistol may be of a similar nature to that of Fig. 2 with a bolt and other parts applied to the pistol. Thus as seen in Fig. 3 a missile-housing barrel 22 as before mentioned may be screwed into the bore of the pistol and may be fitted with a guide member 26 for a bolt 27 extending in the bore of the pistol and terminating at its rear in an enlargement or head 28.

Encircling the bolt between its head 28 and the shoulder 29 formed by the inner end of the missile barrel neck 23 is a spring 31 adapted to be compressed by the bolt against the shoulder 29 when the pistol is "fired". The missile 9 is secured to the front end of the bolt which may therefore be screw threaded to receive a nut 32 the inner face of which bears against a grommet 33 which closely fits a circular hole formed in the closing wall 13 of the missile.

Upon "firing" of the pistol, the bolt will be forced forwardly under pressure of the gas on the closing wall 13 of the missile. The missile and the bolt 27 move together along the axis of the pistol until such a position is reached that the spring 31 is compressed. At this position the missile will have been projected from the missile barrel 22 to such an extent that a clean cut of the travelling web will have been made. The missile will also have moved forward past venting holes 22a in the missile barrel, allowing spent exhaust gas from the blank cartridge to escape. The spring then returns the missile and bolt to the initial position. Any gas which may be compressed in the device by the returning missile acting as a piston may be vented through a small hole 34 formed in the pistol barrel.

The missile may be of the general form as previously described, but is preferably provided with a device for retaining the sample piece within the leading part of the missile pending removal of the sample for examination. For this purpose a stem 36 with a piercing point may advantageously be formed integral with the nut member 32 and project forwardly therefrom so that the piercing point is slightly to the rear of the leading portions of the cutting edge of the missile. In addition a barb 37 may be pivoted to the stem 36 near its piercing point so that the barb will pass through the travelling web in a collapsed condition and upon return motion of the missile will swing outwardly from the stem 36 and withdraw the sample piece with it.

As indicated in the drawings it is preferred to employ a missile of circular or cylindrical shape for ease of fabrication and also because the resultant circular hole formed in the sheet material is least likely to cause such stress concentrations as would lead to lateral rupture or breakage of the travelling web in subsequent stages of manufacture or processing.

When it is desired to seal the sample from the atmosphere to avoid loss of moisture, oxidation or other phenomena which might be deleterious, a sheet of metal or plastic foil may be held behind the travelling web being

sampled so that the missile pierces the travelling web and the sealing foil, and then reverses its direction of motion so as to withdraw from the travelling web with the sample piece "sandwiched" or captive within the missile.

In applying the invention for use with other kinds of pistol-like projectors, use may be made of an adaptor as illustrated in Fig. 5 which consists of a tubular member 38 having a screw threaded portion 38a at one end for connection to the barrel of the pistol-like projector and a screw threaded socket portion 38b at the other end to receive the screw threaded neck 23 of the missile barrel 22.

It is to be understood that a strong spring could be employed in place of gas pressure (Fig. 1) or a blank cartridge (Figs. 2 and 3), a suitable catch releasable by a trigger or the like being adapted to hold the spring in a compressed condition ready to expel the missile at high velocity from its housing.

The invention enables sample or test pieces to be removed from sheet material which may be moving at relatively high speed, say up to 1,000 feet per minute, or even higher. Sample pieces can be readily obtained from any desired positions of the travelling web both lengthwise and transversely.

Where it is desired to test for moisture content, the invention permits of high accuracy as the sample or test piece may be sealed immediately it is removed from the parent material.

For fragile material such as thin plastic film or wet paper products, the sample pieces are removed without danger of tearing the travelling film or sheet.

Having now described our invention, what we claim as new and desire to secure by Letters Patent is:

1. A method of removing sample pieces from material, comprising continuously moving a flat side of a wide sheet of material without a backing support past a cylindrical member containing a missile provided with an endless cutting edge, projecting the missile through the traveling sheet at such velocity that a sample piece of the sheet corresponding to the shape and size of said cutting edge is clearly cut from the sheet without tearing the sheet or interfering with its continued travel, and automatically capturing said sample piece within the missile after it has been cut from the traveling sheet.

2. A method of removing sample pieces from a traveling web of sheet material comprising continuously moving a sheet of material past a projectile device containing a hollow missile having an endless cutting edge, projecting or firing the missile through the traveling sheet at such velocity that a sample piece of the sheet corresponding to the shape and size of said cutting edge is clearly cut from the sheet and automatically captured within the missile without tearing the sheet or interfering with its continued travel.

3. A method according to claim 1, including the step of sealing each sample piece after it has been cut from the travelling sheet within the missile against loss of moisture or change of physical properties.

4. A method according to claim 1, wherein the missile is projected completely through the travelling sheet from one side to the other side and the missile with the sample piece therein is brought to rest at the last mentioned side of the sheet.

5. A method according to claim 1, characterised by causing the missile, after it has cut the sample piece from the travelling sheet, to reverse its direction of motion so that the missile with the sample piece retained therein is withdrawn through the sheet, and then bringing the missile to rest with the sample piece retained therein.

6. A method according to claim 1, wherein a sheet of protective material is arranged behind the travelling sheet, characterised by causing the missile to pass through said sheet after it has cut a sample piece from the travelling sheet, so that a piece of said protective material will be removed from the sheet and adhere to the adjacent surface of the sample piece.

7. A device for removing sample pieces from a traveling web of sheet material comprising a hollow missile having an endless cutting edge at its forward part, a barrel member adapted to slidably accommodate said missile, said barrel having means of attachment to a pistol-like instrument having manually controlled means for causing the missile to be projected from said barrel, means for automatically reversing the motion of the missile in said barrel, and a member carried by the missile for withdrawing material severed by said missile.

8. A device for removing sample pieces from a traveling web of sheet material, comprising a housing, a hollow missile in said housing having an endless cutting edge at its forward part, means to forcibly expel said missile from said housing, means including a spring for automatically reversing the motion of said missile subsequent to the action of said first mentioned means, and a barb on said missile to engage the sample material severed by said missile.

9. A device according to claim 8, wherein said missile is provided with a centrally located, longitudinally extending, stem provided with a sharpened point adapted to pierce a travelling web, said barb being pivotally attached to said stem for penetration during forward movement of said missile and engagement with material pierced by said stem upon retraction of said missile.

10. In a device as set forth in claim 8, wherein the stem extends centrally and longitudinally of the missile and wherein said barb is pivoted to said stem adjacent its sharpened point.

11. An apparatus for removing sample pieces from a traveling web of sheet material comprising in combination, means for receiving the sample pieces, means for continuously moving the web of sheet material in front of said receiving means, a hollow missile of substantial depth from its forward end to its rear end having an endless sharpened cutting edge at its forward end and a

transverse wall near its rear end, a barrel member adapted to slidably accommodate said missile, said barrel member having means for attachment to a pistol-like instrument, and said instrument having manually controlled means for causing the missile to be projected in free flight from said barrel at such a velocity that it will cut with its endless sharpened cutting edge and capture against said transverse wall a piece from the traveling sheet without tearing the sheet or interfering with its continued travel, 10 said piece being brought to rest within the said receiving means.
